(57) **CLAIM**

The ornamental design for a solar mount light rail, as shown and described.

DESCRIPTION

FIG. 1 is a left perspective view of a solar mount light rail according to the design;

FIG. 2 is a right perspective view thereof;

FIG. 3 is an end view thereof, the opposite end view being a mirror image;

FIG. 4 is a right side elevational view thereof;

FIG. 5 is a left side elevational view thereof;

FIG. 6 is a top plan view thereof; and,

FIG. 7 is a bottom plan view thereof.

The break lines in the drawings indicate that the appearance of any portion of the solar mount light rail between the break lines forms no part of the claimed design.
